UNITED STATES PATENT OFFICE.

EDGAR S. HARPST, OF TYLER, TEXAS.

FRUIT-PICKER.

SPECIFICATION forming part of Letters Patent No. 405,410, dated June 18, 1889.

Application filed February 7, 1889. Serial No. 299,002. (No model.)

To all whom it may concern:

Be it known that I, EDGAR S. HARPST, a citizen of the United States, residing at Tyler, in the county of Smith and State of Texas, have invented certain new and useful Improvements in Fruit-Pickers; and I do hereby declare the following to be a full, clear, and exact description of the invention, such as will enable others skilled in the art to which it appertains to make and use the same.

The invention relates to fruit-pickers; and it consists in the novel combination of parts, as hereinafter set forth, illustrated in the accompanying drawings, and pointed out in the appended claims.

The primary object of my invention is to provide a picker that may be adjusted in length to suit trees of different heights.

A further object is to provide a picker with a fruit-receptacle, which is constructed of wire gauze or netting to adapt the same to be introduced readily between branches that are close together; and a further object is to provide a picker which is simple in construction and can be cheaply made and not liable to get out of order.

In the drawings, Figure 1 is a side elevation of my improved picker; Fig. 2, a front elevation partly in section; Fig. 3, a rear view 30 of the fruit-receptacle, partly in section; Fig. 4, a vertical section on the line $x-x$, Fig. 3. Fig. 5 is a detail view, partly in section, showing a modification in the construction of the handle and operating-rod.

In the above-described figures of drawings, A indicates the rod or handle, which, as shown in Figs. 1 and 2, consists of a number of sections a , joined together in any suitable manner—as, for instance, by means of screw-threaded ferrules a' —whereby said rod or handle may be increased or decreased in length to adapt the same to be used in trees of different heights.

B indicates a fruit-receptacle, which is constructed and arranged as follows: Fitted upon the upper end of the upper section a of the handle and secured thereto in any suitable manner is a cup-shaped piece b . I have shown a hole and screw therefor, to the upper edge 50 of which is secured wire gauze or netting to form a cylindrical receptacle for the fruit. This receptacle may be made of any suitable

height and carries at its upper edge a stationary cutting-jaw C, secured by rivets, as shown, to the upper edge of the wire-gauze 55 just described. Said fixed jaw C is made, preferably, of the shape shown in the drawings—that is to say, it has the shape of a sector of a sphere, the annular edge c of which is adapted to be secured to the like edge of 60 the wire-gauze. It has a cutting-edge c' , with which is adapted to coact the cutting-edge of another cutting-jaw, presently described. Said fixed jaw C is also provided with two perforated lugs c^2 , through which passes a pin 65 c^3 , upon which is pivoted a cutting-jaw D, the ends of said pin having bearings in arms d , made integral with said jaw D. The latter is made cup-shaped in form and is provided with a sharp annular cutting-edge d' , which 70 is adapted to meet the cutting-edge c' of jaw C when operated in the manner hereinafter described.

In order that the jaw D may automatically open when the fruit has been severed—that 75 is to say, will be in such position that the fruit may be readily inserted—I provide a coiled spring E, one end of which is secured to one of the lugs c^2 and its other end projecting through a suitable opening, as e , in the pivoted jaw D, and bearing upon the inner face of said jaw. It will be seen that by this arrangement when the jaw D is closed in the act of severing the fruit the coiled spring 80 will be wound, and when the pressure has 85 been released from the operating-handle said spring will cause the jaw D to automatically open to be in position for another fruit.

For operating the jaw D, I provide the following means. F indicates a sleeve fitted 90 over the handle A and provided with perforated ears or lugs f^2 . G indicates the operating-rod, consisting of a number of sections g , united together in a manner similar to the sections a of handle A—as, for instance, by 95 means of the screw-threaded ferrules g' . The upper section of the rod is bifurcated, as shown in Fig. 2, the upper ends of the arms g^2 being pivoted to the arms d of the jaw D.

The lower end of the lower section of the 100 rod G is pivoted between the ears f^2 of the sleeve F.

By making the rod G in sections, as described, enables the same to be adjusted in

length when the length of the handle A is adjusted, and by means of the sleeve F and rod G the jaw D can be operated in a very convenient manner.

5. Inasmuch as the receptacle B is constructed of wire gauze or netting, the same would have a tendency to bulge when the fruit accumulates therein, and in order to prevent this and strengthen the receptacle I employ brace-
10 rods H, attached at their upper ends to the fixed jaw and at their lower ends to the piece b.

It will be seen that by constructing the fruit-receptacle of wire gauze or netting and 15 arranging the same at the upper end of and in line with the handle the same can be more readily inserted between branches which are close together than would be the case were the same made of a fabric and suspended in 20 the usual manner. Furthermore, it can be made very cheaply and very light and strong.

Instead of constructing the handle A and rod G in the manner hereinbefore described—that is to say, of sections united at their 25 meeting ends by means of screw-threaded ferrules or the like—the same may be constructed as shown in Fig. 5, wherein I have shown the handle A and rod G as consisting each of two sections, one of which is made 30 tubular, in which is adapted to slide the other section, the two being secured in the adjusted position by means of set-screws a², whereby said handle and rod can be varied in length.

Various other changes may be made in the 35 construction of my device without departing from the principles involved.

Instead of employing a coiled spring to effect the automatic opening of the pivoted jaw a leaf-spring secured at one end to one of the 40 lugs c² and its other end projecting through the opening in the jaw D, might be employed.

The operation of my device may be briefly described as follows: The device having been adjusted to the proper length and placed over 45 the fruit, the sleeve F is slid along down the handle A, and by means of the rod G the jaw D is caused to close over the fruit, and by

meeting the cutting-edge of the jaw C severs the fruit, which drops within the receptacle B. Upon releasing the pressure on the sleeve F the jaw D is caused to open by means of the coiled spring.

Having now described my invention, what I claim as new, and desire to protect by Letters Patent, is—

1. In a fruit-picker, the combination, with a supporting-rod, of the receptacle supported upon the upper end of said rod, said receptacle being constructed of wire-gauze, and provided at its lower end with the cup-shaped piece b, forming the bottom to said receptacle, and at its upper end with the fixed cutting-jaw C, a second cutting-jaw D, pivoted to said receptacle and adapted to co-operate with said fixed jaw, said pivoted jaw being provided 60 with arms d, and the operating-rod bifurcated at its upper end, the arms whereof are pivoted to said arms d, substantially as described.

2. In a fruit-picker, the combination, with the supporting-rod A, made in sections and 70 united by screw-threaded ferrules, of the receptacle B, supported upon the upper end of said rod and in line therewith, said receptacle being constructed of wire-gauze and provided at its lower end with the cup-shaped piece b, forming the bottom to said receptacle, and at its upper end with the fixed cutting-jaw C, a second cutting-jaw D, pivoted to said receptacle and adapted to co-operate with said fixed jaw, said pivoted jaw being provided 75 with the arms d, and operating-rod G, made in sections and united by screw-threaded ferrules, said rod being bifurcated at its upper end, the arms whereof are pivoted to said arms d, and pivoted at its lower end to the 80 sleeve or handle F, adapted to slide upon said rod A, substantially as specified.

In testimony whereof I affix my signature in presence of two witnesses.

EDGAR S. HARPST.
